UNITED STATES PATENT OFFICE.

FELIX PERUTZ, OF PRAGUE, CZECHOSLOVAKIA.

SPINNING APPARATUS.

Application filed April 15, 1922. Serial No. 552,860.

My invention relates to improvements in spinning apparatus and has for its object to increase the drawing capacity of machines known as drawing frames, roving frames, 5 or ring spinning machines and to increase the efficiency of such machines. My invention is particularly useful in the spinning of cotton, although it is not limited in application to such use. I will accordingly 10 describe my invention herein with regard to its application to cotton spinning.

It is customary in the cotton spinning industry to use several separate machines for drawing the cotton sliver or roving but with 15 my invention the drawing capacity of each machine is so materially increased that one or more of the passages of the yarn through such machines may be dispensed with. The yarn produced by these machines, each embodying 20 my invention, will show greater elasticity than yarn now produced, and will not otherwise be diminished in quality. My invention also permits one to use cotton the staples of which are not quite even. It is 25 possible, for example to use Indian staple cotton and American staple cotton mixed together. My invention is equally capable of being used on any one of the machines used in the process of drawing cotton, but is 30 particularly useful on the final machine commonly known as a ring spinning machine or throste. The principle of my invention will be the same when used on any of these machines, the machines themselves, however, 35 being slightly different in construction in order to accomplish their different functions, as is well known in the art.

In the drawings accompanying this specification and forming part hereof, I have 40 shown my invention in its preferred form, which I will now proceed to describe.

Referring to the drawings, Fig. 1 is a cross-sectional view of the drawing rollers in a roving frame equipped with my invention, the view being taken along the line 1—1 of Fig. 3. Fig. 2 is a longitudinal view of a preferred form of rollers No. 2. Fig. 3 is a plan view from above, partly in section, showing the method of applying power to 45 the four usual rollers of a roving frame. Fig. 4 is an end view of the gearing arrangement shown in Fig. 3. Fig. 5 shows a preferred method of joining together the several sections of lower roller No. 2. Fig. 6 is an 50 outline of the drawing rollers in a ring spinning machine, embodying my invention, showing the modifications necessary to apply 55 the invention to such machine.

Referring to Fig. 3, shaft 11, to which power may be applied, is adapted to revolve 60 in journal 11' in the main body portion of a roving machine. Shaft 11 directly drives roller No. 1^b. Small gear 11^a is permanently fastened on shaft 11. This gear meshes with and drives large wheel 12^a which is removably attached to shaft 12 by means of nut 13. The shaft 12 revolves in another journal in the body portion. A smaller gear 12^b is likewise removably fastened to the other end of shaft 12 by means of nut 13'. This 70 gear meshes with and drives gear 14^a, which is fastened to shaft 14. Lower roller No. 4^b is driven directly from shaft 14. Shaft 14 has affixed to it another gear 14^b, which meshes with and drives a lower gear 15^a, 75 which in turn drives gear 16^a located on shaft 16. Shaft 16 directly drives roller No. 3^b. A superimposed gear 17^b is driven by gear 16^a and in turn drives gear 17^a, which is affixed to shaft 17, that shaft 80 directly operating roller No. 2^b. The shaft 17^c to which the gear 17^b is secured is rotatable in bearings which may be mounted on the frame of the device in any suitable manner. To lend clearness to the drawings, 85 the illustration of shaft 17^c and its bearings has been omitted from Fig. 3. Gear 17^a is removably attached to shaft 17. It can be seen from the drawings that power directly applied to shaft 11 and to roller No. 1^b will 90 be transmitted through the system of gearing to the other rollers with the result that these rollers will revolve at different rates of speed, No. 3^b faster than No. 4^b, No. 2^b faster than No. 3^b, and No. 1^b at the greatest speed. The gears 11^a and 12^a are removable and other gears of different sizes 95 can be interchanged. In this way the rollers may be arranged to revolve at whatever relative speed is desired for the particular work needed. The drawing in Fig. 3 shows a preferred method of gearing under which the relative peripheral speed of No. 4^b, 3^b, 2^b and 1^b is 1.00, :1.08, :1.32, :5.60. The result will be that roller No. 1^b will revolve 100 at 8 times the speed of roller No. 4^b, and the sliver or roving passing through these rollers will be drawn 8 times its original length. The drawing capacity of the machine may be modified by re-arrangement of the 2 interchangeable gears. When the machine is the 105 final one used in the process of drawing, the 110

gearing is rearranged so that the drawing capacity will range anywhere from 12 to 35 times.

The roving machine is equipped with 4 pairs of rollers, No. 4, No. 3, No. 2 and No. 1. The upper roller in each pair are referred to by the letter "a", and the lower roller by the letter "b". The lower rollers are operated directly from the gears as shown in Fig. 3 and described in the preceding paragraph. The rollers extend lengthwise, having surfaces which roll upon one another and between which the sliver or roving passes. In the machine as shown all the lower rollers except No. 2^b are ribbed as is usual in the art. The surfaces of such rollers are not apt to collect dust or waste. In the case of the plain rollers No. 2, I have found it distinctly advantageous to provide the upper roller No. 2 with slight depressions intervening between the parts of the roller which are adapted to act, as pulling surfaces for the sliver or roving. These depressions as shown in Fig. 2 of the drawings constitute successive reductions in the roll diameter between the drawing surfaces. These depressions will collect the dust or waste which may be periodically cleaned out. This preferred construction of the rollers No. 2 is illustrated in detail in Fig. 2. The upper and lower rollers have pulling surfaces 37 and 37'. The upper roller is supported at regular intervals by the sledge 18 and the lower roller similarly by the body portion as at 19. Depressions 20 are located between the pulling surfaces of the upper roller. The lower roller No. 1^b is the standard roller used at present in such machine, and has a ribbed surface as shown. Lower roller No. 1^b is preferably constructed with a diameter of from 28 to 32 mm. Lower roller No. 2^b is a smooth roller 14 to 16 mm. diameter. Lower roller No. 3^b is a ribbed standard roller 22 to 25 mm. diameter. Lower roller No. 4^b is a standard ribbed roller 28 to 32 mm. in diameter. Upper roller No. 1^a is a standard plain iron roller covered with a leather surface. A weight 7 is attached to the cylinder. Upper roller No. 2^a is a plain light iron roller of 30 mm. diameter, weighing about 100 grams. Upper roller No. 3^a is also a plain iron roller weighing around 120 grams and of 60 mm. diameter. Upper roller No. 4^a is a standard heavy iron cylinder. The upper rollers No. 2^a, No. 3^a and No. 4^a are located on movable pieces 5, and the lower rollers on movable pieces 5', by means of which the distance between the respective rollers can be adjusted. Light wooden rollers 6 and 6' are located as shown, for the purpose of cleaning upper rollers 1^a, 2^a and 3^a. The upper rollers are ultimately supported by the sledge 18 which is pivoted to the frame at 21. The sledge can be raised

and the upper rollers cleaned or repaired. The lower rollers are ultimately supported by the body portion proper of the machine. I have found it preferable to construct the light lower roller No. 2^b in several sections. The different sections are joined together by means of a screw head such as shown in Fig. 5. One end of a section of roller No. 2^b is formed with an extension 22, the major part of which is screw threaded as shown. A plain end portion 23 of substantial length is located at the end of the extension and a similar plain portion between the end of the section of roller and the beginning of the screw threaded portion of the extension. A corresponding screw threaded recess is located in next adjoining section of the lower roller. I have found that by joining my roller sections in this fashion better results are obtained and less wear results on the threaded portions.

In operating the roving machine the sliver or roving is fed from the right, as shown in Fig. 1 by the arrow. The sliver or roving is caught and pulled by the rollers which, as they move at different speeds, stretch or draw the sliver or roving as it passes through the machine according to the speed of rotation of the successive rollers. It has been customary heretofore to use drawing rollers of approximately the same weight and size. In my invention, however, only the pairs of rollers No. 1 and No. 4 are of the normal heavy type which unyieldingly pull the sliver or roving without permitting any give or slip. The interior pairs of rollers No. 2 and No. 3 are so made that the sliver or roving is pulled yieldingly between these rollers. For this purpose the upper rollers 2^a and 3^a are made very light so as to give a slipping or yielding pull. By the term "yielding pull" used throughout the specification and the claims is meant that the roving is drawn between certain of the pairs of rollers without the full effect of the rotation of both upper and lower rollers at full force thereupon. This yielding pull is accomplished by mounting the upper rollers of each pair in vertical slots whereby such rollers are free for vertical movement. Inasmuch as such mounting of rollers is well known in the art no detailed description thereof is included herein. As pointed out before, the upper rollers of the end pairs are of such weight as not to yield upwardly when roving passes between the upper and lower rollers. However, the upper rollers of the middle pairs are light relative to the end rollers and therefore will move upward vertically to a slight extent as the roving is drawn between the upper and lower rollers. For this reason when the roving passes between the upper and lower rollers of each of the middle pairs the upper rollers thereof will yield upwardly a slight amount but will

at the same time pull the roving to some extent; hence the term "yielding pull". This is particularly true of the pair of rollers No. 2 of which the upper roller 2^a and lower 5 roller 2^b preferably are made with plain surfaces and are not ribbed. The sliver or roving is drawn by these light rollers, because of their yielding pull, in a more effective manner and without danger of breaking the 10 cotton between the cylinders. Another feature of the pair of rollers No. 2 which results from their small size construction is that they can stand in close proximity to the 15 pair of final delivery rollers No. 1 and in the same way the pair of rollers No. 3 can stand close to the pair of rollers No. 2. This allows the cotton to be conducted through the machine in a better manner and prevents injury to the yarn. When a section of yarn is 20 pulled unyieldingly at one end and yielding- ly at the other and when the section is small enough so that the individual fibres of the cotton are subjected to the unyielding and the yielding pull at the same time, the yarn 25 is drawn smoothly and efficiently, the fibres are smoothed out and the curling or fraying of such fibres is prevented. In this connection it should be noted that I have used the word pull to include the function of the 30 individual-rollers when travelling at different speeds, in drawing, in cooperation with its next succeeding or next preceding rollers, the section of sliver or roving between the two rollers. The pulling includes both the 35 forward pull by one roller and the dragging pull by the other, and I have so used the term pull throughout the claims and specification.

I have shown my roving machine equipped 40 with four pairs of rollers the two outer of which are adapted to give the yarn an un- yielding pull, and the two inner rollers a yielding pull. I have found that the use of only one pair of light interior rollers with 45 two heavy outer pairs of rollers does not give as satisfactory results. The drawing by means of three rollers instead of by four can- not be in as gradual a manner. The light in- 50 terior roller must carry more of a burden and being of light construction it often breaks down under the work. This difficulty is obviated by the use of two interior rollers and preferably by the use of two light interior rollers adapted to give a yield- 55 ing pull.

In the machine illustrated in Figs. 1 and 60 3 the distances shown are adapted for 1 inch staple cotton. I have found the distances shown in the drawings between the different pairs of rollers are well adapted for the work and produce the best results for use with 1 inch staple cotton, for which such machine was designed. These distances are as fol- 65 lows: From pairs of rollers No. 4 to 3, 33 mm.; from No. 3 to 2, 24 mm.; from pairs

No. 2 to 1, 22 mm. These distances are taken between the centers of the respective rollers and as stated are based upon 1 inch staple cotton. If cotton of different staple is to be drawn, these distances should be ad- 70 justed in proportion to the length of staple. The actual measurements between the various pairs of rollers thus vary relatively to the length of staple used. The distances, however, may be varied without serious loss 75 of efficiency to a certain extent but those above given produce the best results accord- ing to my experience. In particular the distances between the pairs of rollers No. 2 and No. 1, placed at 22 mm. should be closely 80 followed as the pair of rollers No. 2 in order to secure the best results should be in close proximity to the pair of rollers No. 1.

In Fig. 6 I have shown in outline my invention as used on the last of the drawing 85 machines commonly called a ring spinning machine or throste. This apparatus is con- structed on the same principle as in the rov- ing machine shown in the previous figures, except that the cotton roving is arranged to 90 pass along a downward slope during the drawing process. The roving enters into this machine in well prepared condition and therefore more drawing can be applied to it. Accordingly the gears which drive the 95 drawing rollers are rearranged so as to drive the pairs of rollers Nos. 4, 3, 2 and 1 at rela- tively greater speeds to one another than in the preceding machines. As before, the upper and lower rollers of the four pairs 100 of rollers are indicated by the addition to the numerals of *a* and *b* respectively. The usual minimum ratio between the speeds of the pairs of drawing rollers Nos. 4, 3, 2 and 1 is as 1.00, 1.18, 1.52 and 9.2 giving a draw- 105 ing capacity of 16.5. This can be increased as high as 1.00, 1.3, 1.8 and 14, which will draw the cotton 33 times. In other respects the machine is similarly constructed to its companion machine shown in detail in Figs. 110 1 and 3.

What I claim as new and desire to secure by Letters Patent is:

1. In spinning apparatus means for draw- 115 ing sliver consisting of four pairs of draw- ing rollers, each pair comprising an upper and a lower roller between which the sliver is adapted to pass, and means adapted to rotate said pairs of rollers at successively greater peripheral speeds, the two outer of 120 said pairs of rollers being adapted to pull the sliver or roving unyieldingly and the two inner pairs of rollers being adapted to pull said sliver yieldingly.

2. In spinning apparatus means for draw- 125 ing roving consisting of four pairs of draw- ing rollers, each pair comprising an upper and a lower roller between which the roving is adapted to pass, and means adapted to rotate said pairs of rollers at successively greater 130

peripheral speeds, two heavy outer rollers adapted when cooperating with their respective lower rollers to pull said roving unyieldingly and two light upper rollers adapted with their respective lower rollers to pull said roving yieldingly.

3. In spinning apparatus, means for drawing sliver consisting of four pairs of drawing rollers between which the sliver is adapted to pass, said pairs of rollers being No. 4, No. 3, No. 2 and No. 1, and means adapted to rotate said pairs of rollers at successively greater peripheral speeds, each of said pairs of rollers comprising an upper and a lower roller, said upper rollers comprising two heavy outer rollers, No. 4 and No. 1 adapted when cooperating with their respective lower rollers to pull said sliver unyieldingly and two light inner upper rollers No. 3 and No. 2 adapted when cooperating with their lower rollers to pull said sliver yieldingly, said pairs of rollers positioned apart at substantially the following distances relative to the staple, based upon one inch staple cotton; No. 4 to No. 3—33 mm.; No. 3 to No. 2, 24 mm.; No. 2 to No. 1—22 mm.

4. In spinning apparatus, means for drawing roving consisting of four pairs of drawing rollers, each pair comprising an upper and a lower roller between which the roving is adapted to pass, means adapted to rotate said pairs of rollers at successively greater peripheral speeds, the two outer of said pairs of rollers being adapted to pull the roving unyieldingly and the two inner pairs of rollers being adapted to pull said roving yieldingly, one of said pair of inner rollers being positioned at the relative distance of not over 24 mm. from said delivery rollers, and the other of said pair of inner rollers being positioned at the relative distance of not over 30 mm. from said first mentioned pair of inner rollers, said relative distances being based upon one inch staple cotton.

5. In spinning apparatus, means for drawing roving consisting of four pairs of drawing rollers, each pair comprising an upper and a lower roller between which the roving is adapted to pass, and means adapted to rotate said pairs of rollers at successively greater peripheral speeds, the two outer of said pairs of rollers being adapted to pull the roving unyieldingly and one of the two inner pairs of rollers being adapted to pull said roving yieldingly, one pair of said outer rollers being initial rollers and the other pair delivery rollers, the positions of the pairs of rollers in relation to one another being adjustable.

6. In spinning apparatus, means for drawing sliver consisting of four pairs of drawing rollers, each pair comprising an upper and a lower roller between which the sliver is adapted to pass, and means adapted to

rotate said pairs of rollers at successively greater peripheral speeds, the two outer of said pairs of rollers being adapted to pull the sliver unyieldingly and the two inner pairs of rollers being adapted to pull said sliver yieldingly, one pair of said outer rollers being initial rollers and the other pair delivery rollers, the relative proximity of the pair of inner rollers next preceding said delivery rollers to said delivery rollers and of the other pair of inner rollers to said first mentioned pair of inner rollers, being relatively adjustable to the staple used in said sliver or roving.

7. In spinning apparatus means for drawing sliver consisting of four pairs of drawing rollers, each pair comprising an upper and a lower roller between which the sliver is adapted to pass, and means adapted to rotate said pairs of rollers at successively greater peripheral speeds, the two outer of said pairs of rollers being adapted to pull the sliver unyieldingly and the two inner pairs of rollers being adapted to pull said sliver yieldingly, said rollers being positioned so as to cause the individual fibres of said sliver to be drawn a plurality of times by an unyielding pull and a yielding pull combined.

8. In spinning apparatus means for drawing sliver consisting of four pairs of drawing rollers, between which the sliver is adapted to pass, said pairs of rollers being No. 4, No. 3, No. 2 and No. 1, and means adapted to rotate said pairs of rollers at successively greater peripheral speeds, each of said pairs of rollers comprising an upper and a lower roller, said upper rollers comprising two heavy outer rollers, No. 4 and No. 1 adapted when cooperating with their respective lower rollers to pull said sliver unyieldingly and two light inner upper rollers No. 3 and No. 2 adapted when cooperating with their lower rollers to pull said sliver yieldingly, said upper rollers having plain surfaces and said lower rollers having ribbed surfaces except said lower roller, No. 2, which is provided with a plain surface, said lower roller No. 2 being formed in sections with means of joining together the several sections consisting of an extension to one end of a section having a screw threaded portion and an exterior plain portion of substantial length.

9. In spinning apparatus, means for drawing roving consisting of four pairs of drawing rollers, between which the roving is adapted to pass, said pairs of rollers being No. 4, No. 3, No. 2 and No. 1, and means adapted to rotate said pairs of rollers at successively greater peripheral speeds, each of said pairs of rollers comprising an upper and a lower roller, said upper rollers comprising two heavy outer rollers, No. 4 and No. 1 adapted when cooperating with their

respective lower rollers to pull said roving unyieldingly and two light inner upper rollers No. 3 and No. 2 adapted when cooperating with their lower rollers to pull said 5 roving yieldingly, said upper rollers having plain surfaces and said lower rollers having ribbed surfaces except said lower roller, No. 2, which is provided with a plain surface, said upper roller No. 2 being provided with 10 a series of drawing surfaces and a series of intervening depressions adapted to collect waste.

10. The method of drawing sliver by pulling said sliver at more than three points 15 simultaneously, said pulling at a plurality of successive points being of a yielding character and at the final point of an unyielding character.

11. The method of drawing roving by 20 pulling said roving at more than three points, said pulling at a plurality of successive points being of a yielding character and at the final point of an unyielding character.

25. 12. The method of drawing roving by pulling said roving at more than three points, said pulling at a plurality of successive points being of a yielding character and at the final point of an unyielding character 30 the amount of the drawing between the third and the second point being greater than the drawing between the second and the first point, and the amount of the drawing between the final and the third point being in 35 excess of the amount of the drawing between the said third and the said second point and between the said second and the said first point combined.

13. The method of drawing sliver by pull-

ing said sliver at more than three points simultaneously, said pulling at a plurality of successive points being of a yielding character and at the final point of an unyielding character, the amount of the drawing increasing successively in the different drawings. 40

14. The method of drawing sliver by pulling said sliver at more than three points simultaneously, said pulling at a plurality of successive points being of a yielding character and at the final point of an unyielding character, the sliver being drawn simultaneously in three sections, the said sections 50 successively decreasing in length.

15. The method of drawing roving by pulling said roving at more than three points simultaneously, said pulling at a plurality of successive points being of a yielding character and at the final point of an unyielding character, the roving being 55 drawn simultaneously in three sections, the length of the said sections being relative to the staple in said sliver or roving. 60

16. The method of drawing sliver by pulling said sliver at more than three points simultaneously, said pulling at a plurality of successive points being of a yielding character and at the final point of an unyielding character, the sliver being drawn simultaneously in three sections, the said sections 70 successively decreasing in length, the final section being of a length, the relative measurement of which, as based on one inch staple cotton does not exceed 24 mm. 75

In testimony whereof, I have signed my name to this specification.

FELIX PERUTZ.
